(57) **CLAIM**

The ornamental design for an “LED lamp,” as shown and described.

DESCRIPTION

FIG. 1 is a perspective view of the LED lamp;
FIG. 2 is a front view of the LED lamp; and a rear view is not shown since it is symmetrical with the front view;
FIG. 3 is a right side view of the LED Lamp; and a left side view is not shown since it is symmetrical with the right side view;
FIG. 4 is a top view of the LED Lamp; and,
FIG. 5 is a bottom view of the LED Lamp.
